CIGARETTE DISPENSER

Eugene A. Gregg, Cleveland, Ohio

Application April 1, 1947, Serial No. 738,623

8 Claims. (Cl. 312—47)

1

This invention relates to a dispensing device. In the preferred form it is adapted to the dispensing of cigarettes and is configured to simulate a burro or jackass, and representations of certain parts of the jackass are employed as operative parts of the apparatus, whereby the dispenser has not only utilitarian value but also offers the attractions of an entertainment device.

The objectives of the invention are:

To provide a new and improved dispensing device particularly adaptable to cigarettes;

To provide a dispensing device in the likeness of an animal and specifically simulating a jackass;

To provide such a dispenser in which the operation is effected by and accompanied by movements of certain members of the animal, and

To provide an amusement device which is operable to dispense cigarettes.

Other objectives and advantages of the invention more or less ancillary to those enumerated will be apparent to those skilled in the art from the specification and drawings which disclose the preferred embodiment of the invention.

Referring to the drawings:

Fig. 1 is an elevation view;

Fig. 2 is a vertical longitudinal section taken on the median plane, showing the mechanism in its position of rest;

Fig. 3 is a central vertical section taken on the same plane as Fig. 2, showing the mechanism in its operated position;

Fig. 4 is a transverse vertical section taken on the plane indicated by the line 4—4 in Fig. 3;

Fig. 5 is a fragmentary elevation view with parts in section, illustrating particularly the operating lever; and

Fig. 6 is an elevation of the operating lever.

As will be apparent from Fig. 1, the overall appearance of the device is that of a jackass 11 bearing a box 12 on its back. This structure may, as indicated, be made of wood but it may, of course, be molded or cast from plastic or metal or fabricated in any other suitable manner. In the preferred wooden construction a carved wooden piece 13 forms the left side of the head, neck, and body of the animal and the left legs. A generally similar wooden block is carved to form the right portion of the animal, including the right legs, and also the right ear 15. An appropriately shaped piece 16 forms the central portion of the back of the neck and the muzzle. The underpart of the trunk is formed by a block 17. The four pieces 13, 14, 16 and 17 may conveniently be glued together with pieces 16 and 17 serving to space the side pieces from each other and leave a cavity 18 between the side pieces which houses the operating mechanism of the dispenser. The box 12, which is of rectangular form, is composed by a front wall 21, rear wall 22, and side walls 23. The side walls are secured to longitudinally extending rails 24

2

and 25 (Fig. 4) which are fixed in any convenient fashion on top of the side pieces 13 and 14 respectively. The inner surfaces of the rails 24 and 25 are coplanar with the inner surfaces of the side members of the body, these four members thus defining a vertical chute 26 for the cigarettes 27 which are disposed longitudinally in the chute. The upper inner edges of the rails are rounded at 28 to provide a lead-in from the storage chamber 29 defined by the walls of the box. A cover 31 provided with a knob 32 rests on top of the box. A simulated head harness 33 and girth straps 34 made of leather or the like may be cemented to the donkey. A tail 36 is pivoted on a pintle 37 between the side members of the body in the appropriate location.

The operating or dispensing mechanism comprises an ejector 41 which is a rectangular block formed with a longitudinal bore 42 for sliding movement on a guide rod or dowel 43 mounted on the upper surface 44 of the spacer block 17 in any convenient manner. The block 41 is reciprocated by a link 46 received in a slot 47 in the ejector and pivoted thereto by a pin 48. The

other end of the link 46 is hinged to a lever arm 51 formed of heavy wire or the like. The wire is bent at right angles to form a shaft 52 which is journaled in a transverse bore 53 in the head portion of the left side member 13, then bent again at right angles to form an arm 54 inserted and secured in the left ear 56 of the donkey. The head is recessed at 51 to form a shoulder against which the ear is received. The ear thus forms one arm of a lever coupled to the ejector block, and upon pulling the ear forward from the position of Figs. 1 and 2 to the position indicated in dashed lines in Fig. 3 the ejector is moved rearwardly on the rod 43. A coil spring 58 mounted on the horizontal portion 52 of the lever is formed with one extending arm 59 hooked around the lever portion 51 and an upwardly extending portion 61 which bears against the under surface of the wooden block 16. The spring 58 thus acts to resist the ejecting movement and return the block 41 to the forward position shown in Fig. 2, permitting a cigarette to drop through the chute 26 until stopped by the guide rod 43 as shown in Figs. 2 and 4. Upon moving the ear forward the ejector block engages the lowermost cigarette, pushing it through the slot 63 between the side body members. The cigarette in emerging engages the tail 36 and lifts it to the position illustrated in Fig. 3, the cigarette then passing under the tail and being retained in position by the unbalanced weight of the tail until removed by a manual operation.

The dispensing device may be mounted on a baseboard 66. A nail or equivalent stop member 67 restrains the cigarette next to the bottom one from being ejected.

Although the foregoing description is neces-

sarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What I claim is:

1. A dispensing device comprising a generally vertical hopper for objects to be dispensed, a rod mounted transversely of and within the hopper and adapted to support the lowermost object, an ejector reciprocable on the rod, means defining an aperture through which the ejector propels the lowermost object, and means adjacent the aperture bias to move so as to grip the object by the said means and the wall of the aperture.

2. A dispensing device for cigarettes and the like comprising a generally vertical hopper adapted to retain the cigarettes in parallel horizontal relation, a rod mounted transversely of the hopper and adapted to support the lowermost cigarette within the hopper, an ejector reciprocable on the rod, means defining an aperture through which the ejector propels the lowermost object, and means within the aperture for frictionally engaging the object.

3. A dispensing device for objects comprising a body adapted to retain the objects in position for dispensing, an ejector reciprocable in the body, a pivoted ear on the body connected to the ejector for operation thereof, an ejection opening in the body at the opposite end thereof from the ear, and a pivoted tail normally biased by gravity to close the opening and comprising a part within the opening engageable by a dispensed object to raise the tail, the said part thereupon frictionally engaging the object within the opening intermediate the ends of the tail.

4. A dispensing device comprising a body defining a chute adapted to retain a stack of objects to be dispensed, an ejector member reciprocable across the chute, the body being formed with an ejection opening adjacent the path of the member whereby reciprocation of the member is adapted to push an object partially through the opening, and a pivoted member partially within the opening biased to normally close the opening and susceptible to being displaced by the ejected object, the pivoted member being disposed to frictionally engage the object within the opening, said pivoted member being formed with a projecting part intermediate the ends thereof to engage the object.

5. A dispensing device for elongate cylindrical objects comprising a body defining a chute adapted to retain a stack of the objects in a generally horizontal position, an ejector member reciprocable across the lower part of the chute, the body being formed with an ejection opening adjacent the path of the member whereby reciprocation of the member is adapted to push an object partially through the opening, and a gravitationally biased pivoted member partially within the opening normally closing the opening and susceptible to being raised by the ejected object, the pivoted member being disposed to frictionally engage the object within the opening, said pivoted member being formed with a projecting part intermediate the ends thereof to engage the object.

6. A dispensing device for cylindrical articles of given diameter, such as cigarettes, comprising

a generally vertical hopper adapted to retain the cigarettes in parallel horizontal relation; an ejector reciprocable across the lower end of the hopper; means defining an aperture aligned with the path of the ejector through which the ejector propels the lowermost article, the lower wall of the aperture constituting a support for the ejected articles; a lever fulcrummed adjacent the support normally closing the aperture and adapted to be engaged within the aperture and raised by the ejected article, the lever being formed with a prominence remote from the free end of the lever to engage the article, so that the lever acts under gravitational bias to hold the article frictionally by grasping it between the said prominence and the said support.

7. A dispensing device for cylindrical articles of given diameter, such as cigarettes, comprising a generally vertical hopper adapted to retain the cigarettes in parallel horizontal relation, the hopper including a lower portion; a rod extending across the lower portion substantially parallel to the side walls thereof, the spacing of the said walls adjacent the rod being greater than but less than twice the said given diameter, and the distances from the rod to the adjacent walls being less than the said given diameter, so that the lowermost of the said articles normally rests upon the said rod and is retained against falling therefrom by one of the said walls; an ejector reciprocable on the rod; and means defining an aperture aligned with the path of the ejector through which the ejector propels the lowermost article.

8. A dispensing device for cylindrical articles of given diameter, such as cigarettes, comprising a generally vertical hopper adapted to retain the cigarettes in parallel horizontal relation, the hopper including a lower portion; a rod extending across the lower portion substantially parallel to the side walls thereof, the spacing of the said walls adjacent the rod being greater than but less than twice the said given diameter, and the distances from the rod to the adjacent walls being less than the said given diameter, so that the lowermost of the said articles normally rests upon the said rod and is retained against falling therefrom by one of the said walls; an ejector reciprocable on the rod; and means defining an aperture aligned with the path of the ejector through which the ejector propels the lowermost article, the lower wall of the aperture constituting a support for the ejected articles; a lever fulcrummed adjacent the support normally closing the aperture and adapted to be engaged within the aperture and raised by the ejected article, the lever being formed with a prominence remote from the free end of the lever to engage the article, so that the lever acts under gravitational bias to hold the article frictionally by grasping it between the said prominence and the said support.
